Primary Examiner — Andrew T Nemeth(74) *Attorney, Agent, or Firm* — Nitin Kaushik(57) **CLAIM**

The ornamental design for a bird feeder, as shown and described.

DESCRIPTION

FIG. 1 is a front perspective view of a bird feeder, showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is an enlarged view of area 8 FIG. 1;

FIG. 9 is an enlarged view of area 9 FIG. 1;

FIG. 10 is an enlarged view of area 10 FIG. 1;

FIG. 11 is an enlarged view of area 11 FIG. 1; and,

FIG. 12 is an enlarged view of area 12 FIG. 1.

The broken lines in the drawings illustrate portions of the bird feeder, and the location and bounds of the enlarged drawing view. None of the broken lines form part of the claimed design.

1 Claim, 12 Drawing Sheets(56)
